STARTING DEVICE FOR TOY ENGINES

John W. McRoskey, West Los Angeles, and Leonard H. McRoskey, Los Angeles, Calif., assignors to Republic Tool & Die Corporation, Los Angeles, Calif., a corporation of California

Application June 24, 1957, Serial No. 667,357

14 Claims. (Cl. 185—37)

This invention relates to starting devices for starting toy engines of low mass and high revolutions per minute operation, which engines are employed to drive a toy, such as, for example, a toy engine driven airplane, wherein the engine is ordinarily started by spinning the propeller or by the use of the recoil type starter.

The present invention avoids difficulties and danger to fingers encountered in the use of the old method of starting toy engines by flipping the propeller forwardly by application of a finger thereto and has for an object the provision of a starting device which is simpler and less expensive than the recoil type of toy engine starter which has a one-way clutch and a pull cord which is pulled outwardly to effect a number of starting revolutions of the engine crankshaft.

To effectively start a toy engine by use of the propeller flipping technique requires exercise of skill by the operator because of the rapidity with which the starting force must be applied to the propeller in order to attain a suitable compression in the engine cylinder. It is an object of the invention to provide a simple and effective starting device which requires no skill on the part of the operator and which gives an effective and consistent starting action each time the device is employed.

It is an object of the invention to provide a starting device wherein an efficient starting action is accomplished without the necessity of the operator applying forward force to the impeller in a quick, instantaneous manner as required in the old practice of flipping the propeller by use of a finger, or by pulling out the cord of a starting device so as to effect the forward rotation of the engine shaft as the pull cord is pulled outwardly. In the present device, the energy for rotating the engine shaft forwardly is accumulated and stored in a spring, and when this energy is released, a very quick or instantaneous and consistent rotation of the engine shaft in forward direction is obtained so that the piston moves very rapidly through several compression strokes.

It is an object of the invention to provide a starting device for a toy engine provided with a clutch having a rotatable part surrounding the engine shaft and having means for effecting engagement of the rotatable part with the shaft when the part is rotated forwardly and when the shaft is rotated in reverse direction, there being spring means connected to the rotatable part and to a stationary member so that when the shaft is rotated in reverse direction the spring will be wound and energy stored therein, the spring, when the shaft is released, rotating the rotatable part forwardly and expending its energy in rotating the shaft in forward direction to start the engine. In the use of the device, the operator manually rotates the propeller rearwardly at any desired speed. This rearward rotation of the shaft causes engagement of the one-way clutch so that the rotatable part of the clutch will be rotated in reverse direction and the spring wound. Then, the operator quickly releases the propeller so that the force of the spring may rotate the shaft in forward, engine-starting direction. In the use of the invention, the

operator is not required to quickly or instantaneously apply a force. He may revolve the propeller slowly in reverse direction, but when he releases his hand from engagement with the propeller, the force of the spring very rapidly rotates the shaft through a number of revolutions, to give an optimum engine-starting effect without the exercise of skill or undue effort on the part of the operator. The starting effect delivered by the device is consistent because the forward engine-starting rotation of the shaft is effected by the spring. Also, the danger of reverse rotation, or kickback, of the engine crankshaft is practically avoided because of the manner in which the starter, upon release of the propeller, rapidly rotates the crankshaft in forward direction through several compression cycles.

Further objects and advantages of the invention may be brought out in the following part of the specification wherein details of construction have been explained for the purpose of providing a complete disclosure, without intending, however, to limit the scope of the invention which is defined by the appended claims.

Referring to the accompanying drawings which are for illustrative purposes only:

Fig. 1 is a perspective view of a toy engine driven airplane equipped with the starting device;

Fig. 2 is an enlarged fragmentary sectional view showing the manner in which the starter is mounted in a position surrounding the forwardly projecting portion of the engine crankshaft;

Fig. 3 is a sectional view taken as indicated by the line 3—3 of Fig. 2;

Fig. 4 is a sectional view taken as indicated by the line 4—4 of Fig. 2;

Fig. 5 is a perspective view of the friction element of the device;

Fig. 6 is a partly sectioned view showing an alternative form of the invention; and

Fig. 7 is a cross-section taken substantially as indicated by the line 7—7 in Fig. 6.

The toy airplane 10, shown in Fig. 1, has mounted near the forward end of its fuselage a toy engine 11 adapted to drive a propeller 12. This toy engine is of the type which has moving parts of low mass and being capable of extremely high speed of rotation. In Fig. 2 the front end wall 13 of the engine crankcase is shown with a tubular extension projecting from the front engine wall 16 and with the front portion of the crankshaft 14 projecting therefrom.

The projecting portion of the shaft 14 is stepped so as to provide a relatively large cylindrical portion 14a, a splined cylindrical portion 17 projecting forwardly from the portion 14a and a stem 18 projecting forwardly from the splined portion 17. The forward end of the stem 18 is provided with threads 19 to receive a nut 20.

The starting device 21 surrounds the shaft 14 and the tubular extension 15 and includes a rotatable part 22 comprising a sleeve 23 surrounding the cylindrical part 14a of the shaft 14 and being rotatable on the sleeve 15, a clutch plate 24, a friction element 24a, clutch discs 28, a drive member 30, and a disc 25. The sleeve 22 has a non-circular end portion 26 to receive the parts 24 and 25, and these parts 24 and 25, as shown in Fig. 3 have therein openings 27 corresponding to the external shape of the end portion 26 of the sleeve 23 so that the sleeve 23 and the parts 25 and 26 will rotate in unison. Means are provided for automatically effecting driving engagement of the rotatable part 22 with the shaft 14 when the shaft 14 is rotated in reverse direction and when the rotatable part 22 is rotated in forward direction. This means is in the form of the one-way clutch which includes small clutch discs 28 disposed in notches 29 in the clutch plate 24, and the one-way

clutch means further includes the circular drive member 30 which is fixed on the splined portion 17 of the shaft and has an annular wall 31 projecting from its periphery so as to surround the clutch plate 24 and the clutch discs 28. The friction element 24a consists of a thin centrally perforated metal disc having diametrically opposed ridges *r* formed by deforming the thin metal wall of the disc 24a toward the clutch disc 28. The friction element 24a has a small projection *P* engaging the drive member 30 so that the friction element 24a rotates with the drive member 30 and the protrusions *r* frictionally engage the clutch discs 28 and move them rearwardly with relation to the clutch plate 24 so that the discs 28 will be jammed between the cam edges 46 of the clutch plate 24 and the annular wall 31 of the drive member 30.

A resilient member comprising coiled spring 32 has one end 33 connected to the sleeve 23 of the rotatable part 22 and the other end 34 thereof connected to a stationary member 35 comprising a cup-shaped housing having an end wall 36 which rests against the face 16 of the engine housing, and a peripheral cylindrical wall 37 which surrounds the spring 32 and the disc 25. The housing 35 is prevented from rotation by engagement with a pin-like lug 38 which projects from the engine housing into an opening 39 in the end wall 36. The drive member 30 has a hub 40 which is fixed on the splined portion 17 and which projects into the forward end of the sleeve 23. The outer, rightward face of the drive member 30 has serrations 41 for making a good driving engagement with the hub 42 of the propeller 12 when the propeller hub is clamped thereagainst by the nut 20. The nut 20 also has the function of holding the complete starter assembly in place on the tubular extension 15 which projects for the crankcase end wall 13.

The forward direction of rotation of the propeller 12 and of the engine shaft 14 is counterclockwise as viewed from a position forwardly of the propeller. The drive member 30 rotates with the crankshaft 14 and, therefore, when the crankshaft 14 is rotating forwardly, as indicated by the arrow 44 of Fig. 3, the clutch discs 28 will rest against the end walls 45 of the clutch plate notches 29. Therefore, at this time there is no driving engagement between the shaft 14 and the rotatable part 22, and the shaft 14 is rotated freely by the engine to operate the propeller 12 in forward direction.

Should the propeller 12 and the shaft 14 be rotated reversely, or in clockwise direction, the clutch discs 28 will be carried in clockwise direction by the ridges *r* of the friction means 24a from the positions in which they are shown in Fig. 3 whereupon they will be moved outwardly by the cam edges 46 of the clutch plate 24 into tight engagement with the annular wall 31 of the drive member 30, effecting a clutching engagement between the parts 24 and 31 so that the clockwise rotation of the propeller 12 will be transmitted to the clutch plate 24 which is a part of the rotatable part 22. As shown in Fig. 4, the spring 32 is coiled in such direction that clockwise rotation of its inner end 33, indicated by an arrow 43, will wind the spring 32.

When starting of the engine 11 is desired, the operator, after priming the engine and making the proper electrical connections therewith, rotates the propeller 12 in reverse (clockwise) direction. The one-way clutch means described in the foregoing makes driving engagement between the drive member 30 and the rotatable part 22, so that the rotatable part will be revolved in reverse direction, as indicated by the arrow 43 of Fig. 4, thereby deforming or winding the spring 32 and storing energy therein. The operator then quickly moves his hand away from the propeller 12, releasing the same so that the force of the spring 32 will rotate the rotatable member 22 in counterclockwise direction, this counterclockwise rotation being transmitted through the one-way

clutch means to the engine shaft to revolve the same forwardly through several revolutions. The action of the spring, when the propeller 12 is released, as described in the foregoing, is to rotate the shaft 14 at such relatively high velocity that the piston of the engine 11 will be carried rapidly through a number of compression cycles. When the spring 32 has unwound after discharging its energy, the rotatable part 22 will be held stationary while the shaft 14 and its supported parts are free to continue their forward, counterclockwise, rotation owing to the release of the one-way clutch means which consists of the movement of the clutch discs 28 in counterclockwise direction into engagement with the end walls 45 of the notches 29.

In the form of the invention disclosed in Figs. 6 and 7, there is an engine 55 having a crankshaft 56 which has a propeller 57 fixed on the projecting end thereof. The device has a separate shaft 58 which is connected to the crank mechanism of the engine shown as a crankshaft 56 so as to rotate in unison therewith. This shaft 58 projects into the crankcase 59 of the engine and has a disc 60 supported on its inner end. The disc 60 has therein an eccentric opening 61 to receive the crankpin 62 which is connected to the crankshaft 56. A starter 63 is disposed in a position surrounding a portion of the shaft 58 adjacent the rear face of the crankcase 59. This starter 63 has a sleeve 64 which is rotatable around the axis of the shaft 58 and is connected to one end of a spring 65 which has its other end connected to a cup-shaped housing 66. The spring 65 is oriented so that when the sleeve 64 is rotated in reverse direction, the spring will be wound, and unwinding of the spring 65 will rotate the sleeve 64 in forward or counterclockwise direction.

A drive member 67 is fixed on the shaft 58 in a position adjacent the housing 66 and is provided with a cavity 68 faced toward the housing 66. In this cavity 68 there is a clutch plate 69 of noncircular form, having an opening 70 which receives an end portion of the sleeve 64. The clutch plate 69 has internal clutch notches 71 communicating with the opening 70 and having therein clutch discs 72 adapted to be moved by the cam edges 73 of the notches 71 into clutching engagement with the outer surface of the sleeve 64, when reverse rotation of the shaft 64 acts through the drive member 67 to rotate the clutch plate 69 in rearward direction.

The notches 71 have end walls 74 which extend radially and which engage the clutch discs 72 when the shaft 64 and the clutch plate 69 are rotated in forward direction, the clutch plate 69 and the clutch disc 72 then revolving freely around the sleeve 64. The cam edges 73 extend spirally from the outer ends of the end walls 74 of the notches 71 toward the external surface of the sleeve 64.

The starting of the engine shown in Fig. 6 is accomplished in the following manner. The operator applies reverse rotation to the propeller 57. This reverse rotation is transmitted through the crankshaft 56 to the shaft 58 which will then rotate the clutch plate 69 in reverse direction, indicated by the arrow 75 of Fig. 7, moving the cam edges 73 in such direction that they will force the cam discs 72 into frictional engagement with the outer surface of the sleeve 64, to drive the sleeve 64 in reverse direction so that the spring 65 will be wound. Then, when the operator releases the propeller 57, the spring 65 will unwind and rotate the shaft 58 in forward direction. Through its connection with the crankpin 62, the forwardly rotating shaft 58 will drive the crankshaft 56 rapidly forwardly to produce a number of compression cycles due to the resulting movement of the engine piston 70 within its cylinder.

We claim:

1. In a starting device for a toy engine characterized by having moving parts of low mass and high revolutions per minute, said engine having a power delivery crankshaft rotatable in forward and rearward directions: a

rotatable part surrounding said shaft; one-way clutch means for connecting said shaft and said part when said shaft is rotated in rearward direction and when said part is rotated in forward direction; and a spring having one end connected to said rotatable part and its other end connected to a stationary member so that said spring will be wound when said part is rotated in rearward direction by rearward rotation of said shaft transmitted through said one-way clutch means to said part from said shaft, said spring, upon release of said shaft, applying its energy through said rotatable part and said one-way clutch means to rotate said shaft in forward, engine-starting direction.

2. In a starting device for a toy engine characterized by having moving parts of low mass and high revolutions per minute, said engine having a power delivery crankshaft rotatable in forward and rearward directions: a rotatable part surrounding said shaft; one-way clutch means for connecting said shaft and said part when said shaft is rotated in rearward direction and when said part is rotated in forward direction; and a coil spring having one end connected to said rotatable part and its other end connected to a stationary portion of the engine so that said spring will be wound when said part is rotated in rearward direction by rearward rotation of said shaft transmitted through said one-way clutch means to said part from said shaft, said spring, upon release of said shaft, applying its energy through said rotatable part and said one-way clutch means to rotate said shaft in forward, engine-starting direction.

3. In a starting device for a toy engine characterized by having moving parts of low mass and high revolutions per minute, said engine having a power delivery crankshaft rotatable in forward and rearward directions: a rotatable part surrounding said shaft; a drive member fixed on said shaft adjacent said rotatable part; one-way clutch means for connecting said drive member and said part when said shaft is rotated in rearward direction and when said part is rotated in forward direction; and a spring having one end connected to said rotatable part and its other end connected to a stationary member so that said spring will be wound when said part is rotated in rearward direction by rearward rotation of said shaft transmitted through said one-way clutch means to said part from said shaft, said spring, upon release of said shaft, applying its energy through said rotatable part, said one-way clutch means and said drive member to rotate said shaft in forward, engine-starting direction.

4. In a starting device for a toy engine having a power delivery crankshaft rotatable in forward and rearward directions: a rotatable part surrounding said shaft; a drive member fixed on said shaft adjacent said rotatable part; one-way clutch means for connecting said drive member and said part when said shaft is rotated in rearward direction and when said part is rotated in forward direction; and a coil spring having one end connected to said rotatable part and its other end connected to a stationary portion of the engine so that said spring will be wound when said part is rotated in rearward direction by rearward rotation of said shaft transmitted through said one-way clutch means to said part from said shaft, said spring, upon release of said shaft, applying its energy through said rotatable part, said one-way clutch means and said drive member to rotate said shaft in forward, engine-starting direction.

5. In a starting device for a toy engine having a power delivery crankshaft rotatable in forward and rearward directions: a sleeve rotatable around said crankshaft adjacent said crankcase; a drive member fixed on said shaft adjacent the outer end of said sleeve; one-way clutch means for connecting said sleeve to said drive member when said shaft is rotated in reverse direction and when said sleeve is rotated in forward direction; and a spring having one end connected to said sleeve between said one-way clutch means and said crankcase, and having the

other end thereof connected to said crankcase, said spring being placed so that it will be wound by reverse rotation of said sleeve in response to rotation of said shaft in reverse direction, said spring, upon release of said shaft, applying its energy through said sleeve, said one-way clutch means and said drive member to said shaft to rotate the same in forward, engine-starting direction.

6. In a starting device for a toy engine having a power delivery crankshaft rotatable in forward and rearward directions projecting from its crankcase: a sleeve rotatable around said crankshaft adjacent said crankcase; a drive member fixed on said shaft adjacent an end of said sleeve; a clutch plate on said sleeve adjacent the outer end thereof and in spaced relation to said drive member; one-way clutch means between said clutch plate and said drive member for connecting said sleeve to said drive member when said shaft is rotated in reverse direction and when said sleeve is rotated in forward direction; and a spring between said clutch plate and said crankcase having one end connected to said sleeve between said one-way clutch means and said crankcase, and having the other end thereof connected to said crankcase, said spring being placed so that it will be wound by reverse rotation of said sleeve in response to rotation of said shaft in reverse direction, said spring, upon release of said shaft, applying its energy through said sleeve, said one-way clutch means and said drive member to said shaft to rotate the same in forward, engine-starting direction.

7. In a starting device for a toy engine having a shaft projecting from its crankcase, said shaft being connected to the crank mechanism of the engine; a sleeve rotatable around said shaft adjacent said crankcase; a drive member fixed on said shaft adjacent an end of said sleeve; a clutch plate connected to said drive member and surrounding a portion of said sleeve; one-way clutch means between said clutch plate and said drive member for connecting said sleeve to said drive member when said shaft is rotated in reverse direction and when said sleeve is rotated in forward direction, said one-way clutch means comprising a clutch disc disposed between said clutch plate and said sleeve; and a spring between said clutch plate and said crankcase having one end connected to said sleeve between said one-way clutch means and said crankcase, and having the other end thereof connected to said crankcase, said spring being placed so that it will be wound by reverse rotation of said sleeve in response to rotation of said shaft in reverse direction, said spring, upon release of said shaft, applying its energy through said sleeve, said one-way clutch means and said drive member to said shaft to rotate the same in forward, engine-starting direction.

8. In a starting device for a toy engine having a shaft connected with the crank mechanism of the engine: a sleeve rotatable around said shaft; a drive member fixed on said shaft adjacent an end of said sleeve; a clutch plate on said sleeve adjacent an end of said sleeve, said clutch plate having external notches therein; clutch discs in said notches for driving engagement with said drive member when said drive member is rotated in rearward direction; and a spring having one end connected to said sleeve and the other end thereof connected to a stationary part of said engine, said spring being positioned so that it will be wound when said sleeve is rotated in reverse direction by reverse rotation of said shaft, said spring, upon release of said shaft, applying its energy through said sleeve, said clutch plate and said drive member to said shaft to rotate the same in forward, engine-starting direction.

9. In a starting device for a toy engine having a shaft connected with its crank mechanism: a sleeve rotatable around said shaft; a drive member adjacent an end of said sleeve; a clutch plate connected to said drive member; clutch disc means arranged between said sleeve and said clutch plate for connecting said drive member and said sleeve for rotation when said drive member is rotated in reverse direction; and a spring connected to said sleeve so as to be wound when said sleeve is rotated in reverse

direction, said sleeve, when said shaft is released, applying its energy through said sleeve, said clutch disc means and said clutch plate, to drive said shaft in forward, engine-starting direction.

10. In a starting device for a toy engine having a shaft connected with its crank mechanism: a sleeve rotatable around said shaft; a drive member adjacent an end of said sleeve, said drive member having a recess therein faced toward said sleeve; a drive plate in said recess, said drive plate having an opening to receive the adjacent end of said sleeve; clutch disc means arranged between said sleeve and said clutch plate for connecting said drive member and said sleeve for rotation when said drive member is rotated in reverse direction; and a spring connected to said sleeve so as to be wound when said sleeve is rotated in reverse direction, said sleeve, when said shaft is released, applying its energy through said sleeve, said clutch disc means and said clutch plate, to drive said shaft in forward, engine-starting direction.

11. In a starting device for a toy engine having a shaft connected with the crank mechanism of the engine: a sleeve rotatable around said shaft; a drive member fixed on said shaft adjacent an end of said sleeve; a clutch plate on said sleeve adjacent an end of said sleeve, said clutch plate having external notches therein; clutch discs in said notches for driving engagement with said drive member when said drive member is rotated in rearward direction; friction means rotating with said shaft for moving said clutch discs in said notches and effecting driving engagement between said drive member and said clutch plate when said drive member is rotated in said rearward direction; and a spring having one end connected to said sleeve and the other end thereof connected to a stationary part of said engine, said spring being positioned so that it will be wound when said sleeve is rotated in reverse direction by reverse rotation of said shaft, said spring, upon release of said shaft, applying its energy through said sleeve, said clutch plate and said drive member to said shaft to rotate the same in forward, engine-starting direction.

12. In a starting device for a toy engine characterized by having moving parts of low mass and high revolutions per minute, said engine having a power delivery crank-shaft rotatable in forward and rearward directions: a rotatable part surrounding said shaft; one-way clutch means for connecting said shaft and said part when said shaft is rotated in rearward direction and when said part is rotated in forward direction; and a resilient member having one end connected to said rotatable part and its other end connected to a stationary member so that said resilient member will be deformed and energy stored therein when

said part is rotated in rearward direction by rearward rotation of said shaft transmitted through said one-way clutch means to said part from said shaft, said resilient member, upon release of said shaft, applying its energy through said rotatable part and said one-way clutch means to rotate said shaft in forward, engine-starting direction.

13. In a starting device for a toy engine having a shaft connected with its crank mechanism: a sleeve rotatable around said shaft; a drive member adjacent an end of said sleeve, said drive member having a recess therein faced toward said sleeve; a drive plate in said recess, said drive plate having an opening to receive the adjacent end of said sleeve; clutch disc means arranged between said sleeve and said clutch plate for connecting said drive member and said sleeve for rotation when said drive member is rotated in reverse direction; and a resilient member connected to said sleeve so as to be deformed when said sleeve is rotated in reverse direction, said resilient member, when said shaft is released, applying its energy through said sleeve, said clutch disc means and said clutch plate, to drive said shaft in forward, engine-starting direction.

14. In a starting device for a toy engine having a shaft connected with the crank mechanism of the engine: a sleeve rotatable around said shaft; a drive member fixed on said shaft adjacent an end of said sleeve; a clutch plate on said sleeve adjacent an end of said sleeve, said clutch plate having external notches therein; clutch discs in said notches for driving engagement with said drive member when said drive member is rotated in rearward direction; friction means rotating with said shaft for moving said clutch discs in said notches and effecting driving engagement between said drive member and said clutch plate when said drive member is rotated in said rearward direction; and a resilient member having one end connected to said sleeve and the other end thereof connected to a stationary part of said engine, said resilient member being positioned so that it will be deformed when said sleeve is rotated in reverse direction by reverse rotation of said shaft, said resilient member, upon release of said shaft, applying its energy through said sleeve, said clutch plate and said drive member to said shaft to rotate the same in forward, engine-starting direction.
